(57) **CLAIM**

The ornamental design for a watch strap, as shown and described.

DESCRIPTION

FIG. 1 is a rear and right perspective view of a watch strap, showing my new design in a configuration of use;

FIG. 2 is front and right perspective view of the watch strap of FIG. 1, shown in a configuration of use;

FIG. 3 is a front, right, bottom perspective view of the watch strap in FIG. 1, shown in an alternate configuration;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof; and,

FIG. 9 is a bottom plan view thereof.

The broken lines showing a watchcase in FIGS. 1-2 represent environmental subject matter only and form no part of the claimed design.
